Jay Otis Ball,
INVENTOR

UNITED STATES PATENT OFFICE.

JAY OTIS BALL, OF BOGOTA, NEW JERSEY.

FORM OF PLATES AND ROLLERS TO ORNAMENT SHEET MATERIALS.

Application filed August 14, 1924. Serial No. 731,940.

To all whom it may concern:

Be it known that I, JAY OTIS BALL, a citizen of the United States, residing at Bogota, in the county of Bergen and State 5 of New Jersey, have invented a new and novel Form of Plates and Rollers to Ornament Sheet Materials, of which the following is a specification.

The object of the invention is to provide 10 a novel form of plates and rollers to ornament sheet materials such as paper, textile fabrics and the like, and the method of making the same.

The invention provides a method for making 15 plates and rollers for ornamenting sheet materials, which differs from the methods ordinarily used in three important particulars; first, in that one master printing surface is made with all the printing surfaces 20 appearing thereon for all the colors that are desired on the finished product; second, in that several color printing rollers are made from said master printing surface; and third, in that a method is provided for 25 making embossing rollers, when desired, from the master printing surface.

More specifically, the invention provides:

Firstly, for a master printing surface, 30 which may be made either by hand engraving or photo-mechanical processes, all the printing surfaces for all the colors desired on the finished product appearing on the one surface.

Secondly, duplicates, such as electrotypes, 35 stereotypes, transferred and etched duplicates, or the like, are then made from this master printing surface. As many duplicate rollers are made from the master printing surface as may be desired for the several colors; surfaces on said duplicate rollers that would print other areas than desired for the one color on each roller are treated so they will not print, as by routing off projecting surfaces or filling intaglio 40 surfaces. Thus the several color printing rollers are made without engraving each roller separately. It should be noted that difficulties of registration are avoided in 45 that the duplicates of the master printing surface are all in perfect registration.

Thirdly, embossing rollers may be made 50 from the master printing surface, or from portions of it, by making duplicates with hollow portions in the roller for such surfaces as may be desired to be embossed.

Referring now to the accompanying drawing, wherein like reference characters represent corresponding parts, Figure 1 represents a section of the master printing surface, which may be either male or female, such terms being used in the art to refer to raised or intaglio surfaces respectively, as previously described. In this instance a male roller is selected as offering a simple illustration of the application of my invention, although it will be evident that both types of rollers may be used, without departing from the spirit of my invention. The master printing surface may be either hand-engraved or made by the photo-mechanical process; and it will be noted that surface areas appear on this roller for the printing of all the colors desired; "a" representing printing surface to print one color, "b" representing such surface as is desired in another color, and "c" and "d" representing surfaces for printing other additional colors.

Figure 2 illustrates the roller for printing the color surface "a", with all the portions of the roller not necessary for printing the color "a" routed off. Figure 3 represents the section of the roller necessary for printing the color "b", with the portions for printing the other colors rendered 80 inoperative. Figure 4 represents the portion of the roller necessary for printing the color "c"; and Figure 5 represents the portion of the roller necessary for printing the color "d", with other surfaces routed off. 85

It will be evident that these duplicate rollers need not be electrotype rollers; for within the scope of my invention, duplicates of the original master printing surface may be made in other ways; such as, for instance, the taking of impressions from the original master printing surface, transferring them to rollers, and then treating surface areas other than the one necessary to print the one particular color, so that colors 90 not desired will not print. 100

Having thus described and illustrated my invention what I claim is:

1. The method of making an embossing roller comprising the making of a master 105 printing surface having surfaces for ornamenting in several colors, making an embossing roller from this master printing surface and treating said embossing roller so that surfaces appearing on said master 110

printing surfaces not necessary to embossing in accordance with a preconceived design are rendered inoperative on the embossing roller.

5. 2. An embossing roller for ornamenting sheet material comprising a complement of a master printing surface with surface areas

appearing thereon for all the colors in a preconceived design, with such portions in the embossing roller that are not desired to ¹⁰ emboss rendered inoperative in the embossing roller.

JAY OTIS BALL.
